Narrow Fabric Company, West Reading, Pa.,
a corporation of Pennsylvania

Application December 17, 1934, Serial No. 54,449

Term of patent 7 years

To all whom it may concern:

Be it known that I, Otto Eugene Huber, a citizen of the United States of America, residing at Reading, in the county of Berks and State of Pennsylvania, have invented a new, original, and ornamental Design for an Elastic Lace Braid, of which the following is a specification, reference being had to the accompanying drawing, forming part thereof.

Figure 1 shows a face view of a portion of elastic lace braid embodying my ornamental design.

Figure 2 shows a section along line 2—2 of Figure 1.

Figure 3 shows a face view of a portion of the elastic lace braid shown in Figure 1, and illus-

trates the appearance of the lace braid when stretched as in use.

Figure 4 is a section along line 4—4 of Figure 3.

Figures 1 and 3 are enlarged approximately one and one-half times actual size, but which in the reduction to patent size will show the elastic lace braid approximately actual size.

Figures 2 and 4 are enlarged approximately two and one-quarter times actual size.

I claim:

The ornamental design for elastic lace braid as shown and described.

In testimony whereof I affix my signature.

OTTO E. HUBER.
